GARMENT PRESSING MACHINE.
APPLICATION FILED OCT. 5, 1914.

Patented Dec. 29, 1914.

2 SHEETS-SHEET 2.

UNITED STATES PATENT OFFICE.

DAVID C. HALE, JR., OF CINCINNATI, OHIO, ASSIGNOR TO HALE GARMENT MACHINERY COMPANY, OF CINCINNATI, OHIO.

GARMENT-PRESSING MACHINE.

1,122,590.

Specification of Letters Patent. Patented Dec. 29, 1914.

Application filed October 5, 1914. Serial No. 865,067.

To all whom it may concern:

Be it known that I, DAVID C. HALE, Jr., a citizen of the United States, residing at Cincinnati, in the county of Hamilton and State of Ohio, have invented certain new and useful Improvements in Garment-Pressing Machines; and I do declare the following to be a full, clear, and exact description of the invention, such as will enable others skilled in the art to which it appertains to make and use the same, reference being had to the accompanying drawings, and to the letters and figures of reference marked thereon, which form a part of this specification.

This invention relates to garment pressing machines and comprises certain improvements of the garment pressing machine shown and described in my pending application, Serial No. 779,428, filed July 17, 1913.

The present improvements relate to various parts, as will be hereinafter described, and have for their object to increase the efficiency and effectiveness of the machine.

Before entering into a detailed description of the same, reference is first made to the accompanying drawings which are illustrative thereof and of which—

Figure 1 is a front elevation; Fig. 2 is a top plan view of the buck-supporting table; Figs. 3 and 4, respectively, are elevations of sleeve and shoulder pads or bucks; Fig. 5 is a horizontal sectional view of the presser head on the line 5—5 of Fig. 1; Fig. 6 is a vertical sectional view on the line 6—6 of Fig. 5; Fig. 7 is a cross-sectional view of the presser head on the line 7—7 of Fig. 5; Fig. 8 is a top plan view of the clamping rims through means of which the cloths are held over the perforated plate; Fig. 9 is an enlarged sectional view on the line 9—9 of Fig. 8; and Fig. 10 is an enlarged sectional detail of one of the jets through which water is sprayed or inducted to the steam generating spaces in the head.

In a detail description of the invention, similar reference characters indicate corresponding parts both in the description and the accompanying drawings.

It will not be necessary to make more than a brief reference to various parts of the machine which are not directly involved in the present improvements because of the fact

that my pending application contains a more detailed description of such parts.

Fundamentally, the machine consists of a base 1 from which extends laterally an overhanging arm 2 to the overhanging end of which a presser head is swiveled. The presser head in the present instance contains various improvements which render it necessary to present various details which are shown on Fig. 2 of the drawings. Also, a well known feature of the machine, as present in the former application, is the buck- supporting table 3, which is subjected to a horizontal movement as well as a vertical movement, the latter movement being that which raises the buck in contact with the presser head. In my former application, the table 3 is provided with a stationary buck which, owing to its being stationary, is required to subserve the pressing purposes of all parts of the garment. In my present improvements, the buck 4, which is substantially the same in outline as that shown in my former application, is mounted on a head or projection 5 rigidly attached to the table 3. The buck 4, it will be observed, is substantially the length of the presser head 80 which appears above it in Fig. 1 and, owing to a swiveled connection between said buck 4 and the head 5, the buck may be turned at an angle to the plane of the presser head by unscrewing a set screw 6. Such position is shown in Fig. 2. This change in the position of the buck 4 enables a sleeve buck 7 or a shoulder buck 8 to be mounted on the table 3 without interference with the elongated buck 4. For this purpose a socket member 9 is secured in the table 3 to receive the shanks 10 of either of the bucks 7 and 8 as shown in Figs. 3 and 4. This facility for placing different sizes or shapes of bucks in operative relation with the presser head 95 greatly increases the efficiency of the machine by enabling the operation of pressing a garment to be done much more expeditiously and satisfactorily. In Fig. 2, the dotted lines indicate the positions of the sleeve buck 7 and the shoulder buck 8, it being understood that one of these are only in position at a time.

Coming now to a description of the presser head, it may be stated that this constitutes means in a broad sense for generating flash

steam instantaneously and in quantities necessary to properly press a garment and leave it dry as it is taken from the buck. In my former application, the presser head is of this character. Under the present improvements of that feature of the machine, the possibility of the water from which the steam is generated finding its way to the garment is absolutely eliminated, it being impossible for the water to come in contact with the garment at any point before it is thoroughly generated into steam which generation is instantaneous. In my former application, a suitable water pump is illustrated through which water is admitted to the presser head through suitable piping and this water pump is employed in the present machine as improved. Such being the case, it has not been deemed necessary to illustrate the pump mechanism. As shown in Fig. 6, water is introduced from the pump through a nozzle 11 communicating with a pipe 12 through which two parallel pipes 13 connect. The pipes 13 lie on each side of an electrically heated unit 14 which is covered by a copper casing 15 so that the water discharged into the head is prevented from coming into direct contact with the core or heating unit 14. The inner ends of the pipes 13 are provided with nozzles 16 which spray the water within the space occupied by said pipes through jet openings 16'. The base member 17 of the presser head is provided with longitudinal and circumferential flanges 18 to which a wire plate or screen 19 is secured by screws in any suitable manner. Projecting from the lower side of the base plate or member 17 are a series of distance lugs 20 which engage the inner side of the screen plate 19 and these distance lugs 20 and the marginal flanges 18 maintain the wire plate 19 in a straight or level position at all times. Mounted against the lower side of the base plate or member 17 are two other electrical heating units 21 which are held against said plate by a suitable number of clamps 22. Projecting from the upper side of the base plate or member 17 are two vertical flanges 23 which support a top plate 24 said top plate having marginal flanges 25 between which and the flanges 23 of the base plate suitable packing 26 is placed. Between these plates, to-wit, the base plate 17 and the top plate 24, the steam generating space is provided. A multiplicity of nozzles 27 are tapped into the base plate which provide communications for the steam to pass from the space above to the space below the base plate 17. Space-filling bars 28 are placed within the space between the said plates 17 and 24 which serve to contract the steam-generating space and to serve as heat containers. These space-filling bars 28 are recessed throughout their inner edges to provide spaces 29 which surround the heat nozzles 27 and thus permit the steam to enter said nozzles 27 and pass below to the screen plate 19. The top plate 24 is provided with an arch 30 which lies above the heating unit 14, and flanges 31 that project down on the outside of the pipes 13. These flanges 31 do not abut against the base plate 17 but on the contrary they provide for sufficient space for the outward passage of the steam generated within the space occupied by the heating unit 14 and the water pipes 13. It will be seen from this arrangement that these flanges 31 baffle the water discharged from the pipes 13 and retard it until the steam is generated. The outer heating units 21 provide sufficient heat to prevent any condensation after the steam has passed into the spaces on the outside of the flanges 31. Around the outer margins of the flanges 23 of the base plate and marginal flanges of the top plate 24 are a series of apertured lugs 32 which align when said plates are assembled and by means thereof screws are employed to firmly unite said plates. It will be observed from Fig. 7 that the top plate 24 lies a sufficient distance from the ends of the nozzles 27 to permit of a free passage of the steam into said nozzles. On one end of the base plate 17 provision is made for the electrical connections with the heating units, while on the other end provision is made for the water pipe 12 which, as before stated, connects with the pipes 13. Projecting from the upper side of the top plate 24 are apertured lugs 33 which provide for a swivel connection between the presser head and the overhanging arm 2, substantially as shown in my former application.

An outer cover or casing 34 covers the presser head proper and when assembled therewith constitutes a feature of the presser head. This casing is made in two parts and is united to the upper plate 25 by a suitable number of screws which pass through apertured lugs 35 provided at suitable points on the upper side of said plate 25. The said casing is also provided with openings through which the apertured lugs 33 project which, as before stated, provide for the pivotal connection between the head and the overhanging arm 2. The said casing is also provided with a centrally depressed portion 36 lying between the apertured lugs 33 in which the terminal of the arm 2 lies when the head is in position, as shown in Fig. 1. The said casing is further provided with an opening 37 through which the electrical connections pass. When the casing 34 is secured in position, the down-turned marginal edge thereof rests in contact with the surrounding edge of the base plate 17 and at suitable points on opposite sides of said casing and at each end there are provided apertured lugs 38 which receive pins or bolts 39

the lower ends of which are provided with eccentric heads 40. The said pins or bolts 39 are provided with springs 41 which serve to hold said pins upward for a purpose presently described.

Spread over the lower side of the screen plate 19 are two cloths 42 and 43, respectively, the former consisting preferably of an asbestos fabric, shown in wave lines in Fig. 7, and the latter being a suitable cloth spread on the outside thereof and shown in a straight black line in Fig. 7. These two cloths are stretched taut against the screen plate by having their marginal edges secured between a frame which surrounds the outer side of the base plate 17. This frame consists of a male and female member 44 and 45 respectively. The former member is provided with a tapered projection 46 with teeth 47 projected therefrom at suitable points, while the member 45 is provided with a channel 48 into which the tapered projection 46 extends. The edges of the fabric are held between the projection 46 and the channel portion of the frame 45. The two members constituting said frame are shown in Fig. 8. They are held temporarily together, when not in position on the presser head, by eccentric 49 which are mounted in opposite ends of the female frame 45 and may be turned to enter adjacent recesses in the ends of the male frame member 44. The cloth frame as a whole is held in position by the eccentric heads 40 on the bolts 39, before referred to, said eccentric heads engaging shoulders 50 formed at the proper points in the male frame member 44.

As hereinbefore stated, the water to the presser head is supplied intermittently through the pipes 11, 12 and 13 and the steam is instantaneously flashed through the perforated plate and the cloths. The water is confined within the longitudinal spaces between the flanges 23 and the copper casting surrounding the heating unit 14. The steam resulting therefrom is maintained in the form of steam while in the presser head by the additional heating units 21. The electrical connections are substantially as described in my former application.

Having described my invention, I claim.

1. In a machine of the type specified, a presser head comprising a base plate having longitudinal vertical flanges on the upper side thereof and a series of steam orifices communicating with the space below and above said base plate, a top plate mounted above said base plate and having longitudinal flanges extending from the lower side thereof, a heating unit within the space between said flanges of said top plate, and water induction pipes lying between the sides of said heating units and said flanges, substantially as specified.

35 2. In a machine of the type specified, a

presser head comprising a base plate having longitudinal vertical flanges extending from the upper side thereof and longitudinal vertical flanges extending from the lower marginal sides thereof, a perforated plate 70 mounted below said base plate, a top plate supported on the longitudinal flanges on the upper side of said base plate and providing an inclosed space between said base plate and said top plate, said top plate having 75 longitudinal flanges projecting from the lower side thereof into said space, a heating unit extending between said flanges, water induction pipes lying between said heating units and said flanges, and a series of steam 80 orifices in the base plate on the outer sides of the flanges of the top plate and providing a communication between the spaces above and below the base plate, substantially as specified.

3. In a machine of the type specified, a 85 presser head comprising a base plate having longitudinal vertical flanges on the upper side thereof, a plurality of heating units secured to the lower side of said base plate, a perforated plate secured below said heating units, a top plate supported on said flanges, said top plate having downwardly projecting flanges and providing an inclosed space above the base plate which is separated by the flanges on said top plate, a heating 90 unit lying within the space between the flanges of said top plate, water induction pipes lying along the sides of said heating unit and inclosed by the flanges of said top plate, a series of steam orifices in the base 95 plate providing a communication between the spaces above and below the base plate 100 said orifices being arranged on the outside of the flanges of the top plate, and space-filling bars mounted within the space between the base plate and the top plate and contracting the space surrounding said orifices, substantially as specified.

4. In a machine of the type specified, a 110 presser head comprising a base plate having longitudinal flanges projecting from the upper side thereof, heating units mounted below said base plate, a perforated plate mounted below said base plate, a top plate mounted above said base plate and providing an inclosed space thereabove, a heating unit mounted in said space, water induction pipes extending parallel with said heating units on opposite sides thereof, baffle walls inclosing said pipes and heating unit, a series of nozzles mounted on the base plate and projecting into the space on the outside of said baffle walls, said nozzles providing communication between the space above and below the base plate, 115 120 and space-filling bars mounted within the space above the base plate and on the outer side of said baffle walls, said bars having recessed portions surrounding said nozzles, 125 substantially as specified.

5. In a machine of the type specified, a presser head comprising a base plate having down-turned marginal flanges and flanges projecting from the upper side thereof inwardly from the margins thereof, a 5 perforated plate mounted below said base plate and separated by said down-turned flanges, heating unit mounted upon the base plate above said perforated plate, a fabric 10 inclosing the lower side of said perforated plate, a circumferential frame surrounding the margin of said base plate and consisting of two members between which said fabric is clamped, and means for holding said 15 frame members in position against the margins of the base plate, substantially as specified.
6. In a machine of the type specified, a presser head comprising a base plate having 20 down-turned marginal flanges, and vertical flanges projecting from the upper side thereof, heating units secured to the lower side of said base plate, a perforated plate secured to the down-turned flanges of said base plate, 25 a top plate mounted on the vertical flanges of said base plate and providing an inclosed space above the base plate, said top plate having flanges projecting into said space and terminating above the base plate, a heating unit extending between said flanges, 30 water induction pipes lying between said flanges and said heating unit, a series of steam nozzles mounted in the base plate and 35 projecting into the space between the base and top plates, space-filling bars supported
- on the base plate within said space having recesses within which said nozzles lie, and a casing mounted above said base plate, over the top plate, substantially as specified.
7. In a machine of the type specified, a 40 presser head comprising a base plate having a down-turned marginal flange, and vertical flanges projecting from the upper side thereof, heating units mounted upon said base plate, a perforated plate mounted below said 45 heating units, a top plate mounted upon the vertical flanges of the base plate said top plate having downwardly extending flanges which separate the space between the top plate and the base plate, a series of steam 50 nozzles mounted in said base plate and extending into the spaces on the outside of said flanges, space-filling bars within the spaces on the outside of said flanges, a heating unit lying longitudinally within the space between said flanges, water induction pipes lying parallel with said heating unit and between said heating unit and the flanges of the top plate, a cover supported on the base plate, a fabric inclosing the perforated plate, 60 a frame consisting of two members between which the edges of said fabric are clamped, and means on the casing for holding said frame in position, substantially as specified.
- In testimony whereof I affix my signature, 65 in presence of two witnesses.
